UNITED STATES PATENT OFFICE.

JOHN A. SCHEID, OF ROXBOROUGH, PENNSYLVANIA.

DESIGN FOR A TIRE.

Application filed June 26, 1922. Serial No. 2,829. Term of patent 14 years.

To all whom it may concern:

Be it known that I, JOHN A. SCHEID, a citizen of the United States, residing at Roxborough, in the county of Philadelphia and State of Pennsylvania, have invented a new, original, and ornamental Design for a Tire, of which the following is a specification, reference being had to the accompanying drawing, forming a part thereof.

Figure 1—is a partial plan view of a tire showing the design on the tread thereof; and,

Figure 2—is a transverse sectional view of the same.

I claim;
The ornamental design for a tire as shown.

JOHN A. SCHEID.
